UNITED STATES PATENT OFFICE.

THOMAS M. ERWIN, OF VERONA, ASSIGNOR OF ONE-FOURTH TO EDWARD FRIED, OF ALLEGHENY CITY, PENNSYLVANIA.

SPRING-WASHER FOR LOCKING NUTS.

SPECIFICATION forming part of Letters Patent No. 279,088, dated June 5, 1883.

Application filed May 4, 1883. (No model.)

To all whom it may concern:

Be it known that I, THOMAS M. ERWIN, a citizen of the United States, residing at Verona, county of Allegheny, State of Pennsylvania, have invented or discovered a new and useful Improvement in Spring-Washers for Locking Nuts on Bolts; and I do hereby declare the following to be a full, clear, concise, and exact description thereof, reference being had to the accompanying drawings, making a part of this specification, in which—like letters indicating like parts—

Figure 1 is a view in side elevation of my improved spring-washer applied to lock the nuts of a rail-joint, and Fig. 2 is an enlarged view of the spring-washer alone.

My invention relates to spring-washers for locking nuts on bolts; and it consists of a washer, of **S** form, made of a flat steel bar by bending such bar at its ends in the plane of its greatest width to turn round or encircle the bolts, and twisting the bar between its bent ends to secure torsional spring action, as hereinafter more fully described and claimed.

In the drawings, A represents my improved spring-washer, made of a rectangular or flat steel bar of proper length, bent into the **S** form shown, by first bending the hooks or loops *a* on its two ends, the plane of bending being parallel with the flat face of the bar, and both being bent in the same direction, or to the same side of the bar, thus giving the blank a **C** form. The blank is then given a half-twist, thereby reversing the sides or directions of the hook ends, and giving the edges *c e* a spiral turn, extending toward either end to or beyond the point where the nuts bear upon the hook-faces—say, by preference, to or beyond the ends *c'*. As a result of such bending and twisting, the edge *e* forms the inner edge of both hooks and the one to be placed upon the splice-bar D, Fig. 1, or other equivalent bed, while the edge *c*, which makes the spiral overturn from outside to outside of the hooks, is the one against which the nuts E are turned. In screwing up the nuts the raised edges *c c'* are pressed down toward or upon the splice-bar, thereby putting the washer under spring-tension, which will press the

nuts both in the direction of the length of 50 bolt, and also forward in the direction of screwing on. This latter action is due to the upward and outward inclination of the washer, whereby an upward incline is presented to the back edges of the nut as they turn from 55 *c* to *c'*. The spring action thus secured is torsional in its nature, and is due in part to the elevation of the outer edge above the inner in direction across the nut, and also to the spiral lift of the outer edge, *c*, from the 60 ends *c'* toward the center between ends. In some positions of the nut this torsional pressure is operative upon two of the edges or corners of the nut, and in any and all positions it is operative upon at least one rear edge or 65 corner, so that in whatever position the nut may be left, the washer will exert pressure thereon to prevent unscrewing.

I do not claim herein a spring-washer of **S** form, broadly considered, for washers have 70 been made of this form, and also of figure-**8** form, round spring-wire being used, bent upward at the ends or in the middle to give spring action upon the nut. I believe, however, that it is new with me to make an **S** 75 form of spring-washer, a flattened bar being used, and the spring action being secured by twisting the bar between its hooked or looped ends. This spring action is not only stiffer and better applied to the nut to prevent unscrewing than the prior washers referred to, but also better inclines are secured on which the corners of the nut may ride to compress the spring both in screwing up and unscrewing, so that the nut may be turned with a suitable wrench in either direction without other application of force to the washer, and without danger of catching the corners of the nut 80 upon any part of the washer.

My improved washer may be made of comparatively cheap grades of steel, being bent and twisted while hot by any suitable mechanism, and tempered in the usual manner of tempering spring-washers of other forms.

I claim herein as my invention—

1. A spring-washer of **S** form, made of a flat steel bar twisted between its hooked ends, substantially as set forth.

2. A spring-washer of **S** form, made of a flat steel bar twisted between its ends by a half-turn, the same edge of the bar being outermost on both the hooked ends of the washer, substantially as set forth.

3. A spring-washer of **S** form, made of a flat steel bar spirally twisted by a half-turn, such twist extending into or around both its

hooked ends, substantially as and for the purposes set forth.

In testimony whereof I have hereunto set my hand.

THOMAS M. ERWIN.
